FILAMENT CURRENT STABILIZER

Filed Sept. 27, 1944

UNITED STATES PATENT OFFICE

2,518,539

FILAMENT CURRENT STABILIZER

Edward B. Graves, Cleveland, Ohio, assignor to Picker X-Ray Corporation Waite Manufacturing Division, Inc., Cleveland, Ohio, a corporation of Ohio

Application September 27, 1944, Serial No. 555,993

7 Claims. (Cl. 250—103)

1

This invention relates to improved means for stabilizing the current in an X-ray tube.

An object of the present invention is to provide a stabilizer for the current flowing in an X-ray tube including means for absorbing more electrons from the heated tube filament when the tube current increases, the same acting to absorb less electrons from the heated filament when the tube current is less.

Another object of the present invention is to enable the desired tube current to be set substantially instantaneously without waiting for the filament temperature to become stabilized.

Other objects and advantages of the invention will be apparent from the accompanying drawing and description, and the essential features will be summarized in the claims.

The single figure of the drawing shows an electrical diagram illustrating one manner of carrying out my invention.

As is well known in this art, if just sufficient current is supplied to the heated cathode filament of an X-ray tube to supply the desired tube current when the filament is first energized, then as the electrical characteristics of the apparatus fluctuate chiefly due to temperature changes during use, the tube current will vary from the desired value. By my present invention I am enabled to immediately procure and consistently to hold the desired tube current by means of a stabilizing device which will hold the tube current at the desired value as the filament temperature fluctuates. In fact, the device will automatically compensate for changes in tube current so as to maintain the same very close to a pre-selected value.

I have chosen to illustrate my invention as applied to an X-ray tube 10 having a heated cathode filament 11 and an anode or target 12, the tube current being supplied from the secondary 13a of high tension transformer 13, the primary of which 13b is energized from a suitable source L₁, L₂. The filament current is supplied from the secondary 14a of filament transformer 14, the primary of which 14b is energized from the source L₃, L₄ acting through a conventional stabilizer unit 15. A control 16 of the monitor type is illustrated having various settings such as 16a, 16b, etc., for selecting the desired filament current. It will be understood that this control member 16 is usually calibrated in terms of the reading desired on the milliammeter 17 which measures the current flowing in the X-ray tube. Normally, the setting of the control member 16 would provide just sufficient current to

2

excite filament 11 to the degree necessary to provide the desired tube load as indicated on the milliammeter 17. In my present invention, the control member 16, when set for the desired tube load, will overexcite filament 11, that is to say, it will provide a current flow to the filament actually greater than that normally necessary to provide the tube current corresponding to the load set by the operator or the monitor control device 16. My improved device then absorbs sufficient electrons from filament 11 so that the tube current is actually held at the level indicated by the setting of the control 16.

Adjacent the filament 11, I provide an electrode 18 in position to more readily attract electrons from the filament 11 than the target 12. I have found that the electrode 18 may be in the form of an imperforate metal cylinder, but I do not desire to be limited in the specific form of this electrode as I may use other forms which produce the same effect. Means is provided for supplying to the electrode 18 a charge adapted to absorb electrons from the filament 11. The means here shown comprises a transformer 19 having one winding 19a connected by lines 20 and 21 with the filament 11 and the electrode 18 respectively. The other winding 19b of this transformer is energized from the source L₃, L₄ through the stabilizer unit 15 and is preferably controlled by the monitor control member 16 as shown in the drawing.

In circuit with the transformer winding 19b is the winding 22b of a transformer 22 whose other winding 22a is connected in the circuit 23, 17, 24 in the center ground circuit of the secondary winding 13a of the high tension transformer 13. It is well known that where an X-ray tube acts as its own rectifier, the current passes through the tube in one direction only, and under these conditions a direct current milliammeter such as 17 connected in the center ground circuit of the secondary winding of the high tension transformer will indicate the amount of current passing through the X-ray tube. Therefore, the current in the transformer winding 22b is proportionate to the current flowing in the X-ray tube. It follows that the current flowing in the transformer windings 22b and 19b will be proportionate to the X-ray tube current and, therefore, upon an increase or decrease in the X-ray tube current, there will be an increase or decrease respectively in the charge on the electrode 18. The circuits are so designed that with the control device set on taps 16—16a, for instance, the current supplied in the circuit L₃, 16a, 14b, L₄ is

more than sufficient in the absence of electrode 18 to excite filament 11 to produce the tube load indicated at the control setting 16'-16a. Then the circuit L₃, 16', 22b, 19b, L₄ is so designed that a charge will be provided on electrode 18 just sufficient to absorb enough excess electrons from filament 11 to cause the desired tube load to be indicated at 17 as called for by the setting of control device 16. Because the current in 22b and 19b is proportionate to the tube load, it follows that as the tube load increases, electrode 18 absorbs more electrons from filament 11; and as the tube load decreases, electrode 18 absorbs less electrons from filament 18. The circuits are so designed that this action of electrode 18 and its energizing circuit compensates for tube load fluctuations and so holds the tube load substantially constant.

Preferably, taps 16', 16'', etc. are provided on the monitor control 16 in circuit with the transformer windings 19b and 22b so as to vary the charge supplied to the electrode 18 in step with the variation of the current supplied to the filament 11.

While I have shown my invention as applied to an X-ray tube acting as its rectifier, it should be understood that I do not desire to be limited to the application of my invention in this single field only. In other words, my invention is equally applicable to X-ray tubes having other types of energizing circuits. To illustrate what I mean, my invention may be applied to a tube having a fully rectified circuit such as shown in Patent No. 2,189,894, granted February 13, 1940, to Edwin R. Goldfield et al. This Goldfield patent shows a circuit including a milliammeter 9 adapted to show the correct value of the current flowing in the X-ray tube 2. I contemplate the placing of my electrode 18 about the filament 2a of this Goldfield device and the placing of my transformer winding 22a in series with the milliammeter 9 of the Goldfield patent with the rest of my control circuit for my filament 11 and electrode 18 the same as shown in Fig. 1 of my drawings. In other words, I wish to emphasize that the drawing is illustrative of one embodiment, and my device will operate as disclosed providing only that the charge supplied to the electrode 18 varies proportionately to the true load on the X-ray tube.

What I claim is:

1. In a stabilizer for tube current in an X-ray tube having a heated cathode filament, means for supplying current to said filament greater than that necessary to produce the desired current flow in said tube, and means including a circuit responsive to every variation in current flow in said tube at all times and including an electrode adjacent said heated cathode filament for absorbing sufficient excess electrons from said filament to hold current flow in said tube to the desired level as said filament current fluctuates during use.

2. In a stabilizer for tube current in an X-ray tube having a heated cathode filament, the combination of an electrode adjacent said filament, means including a circuit varying in direct relation to current flowing in said tube at all times for energizing said electrode with a graduated charge adapted to absorb electrons from said filament, means for energizing said filament including means for selecting a desired filament current, and means acting concurrently with said current selecting means for varying said first named means.

3. In a stabilizer for tube current in an X-ray tube having an anode and a heated cathode filament and having a circuit between said anode and cathode, the combination of an electrode adjacent said filament, a first transformer, a second circuit for energizing said electrode with a charge adapted to absorb electrons from said filament and including the secondary of said first transformer, a second transformer having one winding in said first named circuit, and a third circuit for energizing the primary of said first transformer, said third circuit including another winding of said second transformer.

4. The combination of claim 3 including variable means for heating said cathode filament, means for varying said last named means including a selector, and means for varying the current flowing in said third circuit operable by said selector.

5. A stabilizer for tube current in an X-ray tube having an anode and a heated cathode filament wherein said tube is energized by a high tension transformer having a secondary with a central grounded circuit, said stabilizer comprising an electrode adjacent said filament to affect electron flow therefrom, a first transformer having a secondary in circuit with said electrode, said first transformer having a primary, stable electrical source means for energizing said primary, and a second transformer having one winding in series in said central grounded circuit, said second transformer having another winding in circuit with said primary of said first transformer.

6. The combination of claim 5 including a third transformer having a secondary in circuit with said heated cathode filament, said third transformer having a primary, electrical source means for energizing said primary, electricity flow control means for each of said electrical source means, and means for concurrently actuating said control means.

7. In a stabilizer for tube current in an X-ray tube having an anode and a heated cathode filament and having a power circuit between said anode and cathode filament, the combination of a stabilizing electrode adjacent said filament and positioned to affect electron flow relative to said filament, a first transformer having a secondary in circuit with said electrode, said first transformer having a primary, first electrical source means for energizing said primary, a second transformer having one winding in said power circuit and having another winding in circuit with the primary of said first transformer, a third transformer having a secondary in circuit with said filament and having a primary, second electrical source means for energizing said last named primary, electricity flow control means for each of said electrical source means, actuating means operatively connected with said electricity flow control means for concurrently actuating both of said control means at one setting, said actuating means being calibrated in terms of desired X-ray tube operating current, said actuating means at a given setting selecting a value for said control means for said second source means for over-exciting said cathode filament for said desired X-ray tube current, and at the same time said actuating means selecting a value for said control means for said first source means for opposing said amount of excitation over the value necessary to produce said desired X-ray tube current.
